METHOD AND APPARATUS USED IN
X-RAYING OBJECTS

Sterling H. Nighswander, Davenport, Iowa, assignor to International Basic Technique Research Institute, Inc., St. Louis County, Mo., a corporation of Missouri

Application October 16, 1946, Serial No. 703,598

13 Claims. (Cl. 250—59)

1

This invention relates to improvements in methods and apparatus that are used in X-raying objects. More particularly, this invention relates to improvements in methods and apparatus that are used to determine the true relative positions of two spaced objects by means of X-rays and X-ray film.

It is, therefore, an object of the present invention to provide an improved method and apparatus for determining the true relative positions of two spaced objects by means of X-rays and X-ray film.

In certain methods of treating persons for various ills and bodily ailments, it is important to determine with considerable accuracy the true relative positions of the top portions of the femur bones of those persons. Obviously, because of the layers of muscle and tissue of those persons, it is impossible to make direct physical measurements of the positions of those particular portions of the femur bones relative to a common base or point. Accordingly, a method has been devised that permits measurement of the true relative positions of the top portions of the femur bones of a person despite the presence of the layers of muscle and tissue of that person and that method utilizes X-rays which pass through the person's muscle and tissue. In practicing that method, it is customary to have the person stand with his or her feet on a leveled surface, and to stand immediately in front of a large size photographic plate while X-rays are projected through his or her body onto the photographic plate. Thereafter, the photographic plate is developed and mounted on the front of an X-ray viewing box. Where the X-ray viewing box is perfectly vertical and where the photographic plate is made precisely parallel to the X-ray viewing box, the positions of the shadows cast on the photographic plate by the top portions of the femur bones can be determined relative to a common base or point. Since the shadows on the photographic plate were cast by the top portions of the femur bones, a determination of the positions of those shadows relative to a common base or point would seem to provide a true determination of the positions of those portions of the femur bones relative to a common base or point. In many instances the determination of the relative positions of the shadows cast by the top portions of the femur bones did corroborate and make definite the determination of the relative positions of those portions of the femur bones that was obtained by other diagnostic methods; but in other instances, the determination of the

2

relative positions of the shadows cast by the top portions of the femur bones disagreed with the determination of the relative positions of those portions of the femur bones that was obtained by the other diagnostic methods.

In some of those other instances, a re-examination of the person's bone structure by means of X-ray photographs showed different relative positions of the top portions of the femur bones, although each time the person had his or her feet on the same leveled surface. Investigation proved that where the photographic plate gave a true indication of the relative positions of the top portions of the femur bones, the persons had stood in such a way that the top portions of the femur bones were equidistant from the photographic plate. Where the photographic plate did not give a true indication of the relative positions of those portions of the femur bones, the persons had stood in such a way that the top portions of the femur bones were not equidistant from the photographic plate. This result is due to the fact that the X-rays emanate from a virtual point source and diverge as they move toward the photographic plate and that, therefore, two horizontally-spaced objects must be at the same level, at the same distance from the photographic plate, and must be disposed at equal distances on opposite sides of the ray-emitting aperture to cast shadows which have the same positions relative to a common base or point. Accordingly, whenever the top portions of the femur bones of a person are at different distances from the photographic plate, the shadows cast by those portions on that plate will not be truly indicative of the relative positions of those portions of the femur bones. In recognition of this fact, it is customary to have the person align his or her body between the ray-emitting aperture and the photographic plate in such a way that the top portions of the femur bones are equidistant from the photographic X-ray plate but this is not possible in all instances because the various bones of a person's body do not have precisely the same positions and proportions in all instances, and there may be some shifting of the various portions of the bone structure relative to each other because of disease or accidental injury. As a result, it sometimes happens that the top portions of the femur bones cannot be set precisely equidistant from the photographic plate and in those instances, distortion of the picture on the photographic plate will result and the shadow cast by the top portion of one femur bone will not bear the same relation to the shadow cast

by the top portion of the other femur bone as that portion of the one bone actually bears to the top portion of the other bone. Consequently, in using the X-ray photographs to determine the relative positions of the top portions of the femur bones, it is necessary to calculate a correction factor based on the angle of divergence of the X-rays and the distances of the top portions of the femur bones from the photographic plate and to apply that correction factor to the data obtained from the photographic plate.

In making his calculation, the diagnostician must remember that the X-rays, which pass through the ray-emitting aperture of the X-ray device diverge vertically and horizontally and will cast shadows that are distorted in both directions. Accordingly, the calculation must take into account both the vertical and horizontal divergence of the X-rays. Consequently, in using X-ray photographs to determine the relative heights of two spaced objects that are not accessible for direct physical measurement, it has become necessary to make complicated and laborious mathematical calculations and determinations before the diagnostician can trust the information obtained from the photographic plate. The making of the mathematical calculations is not only laborious but it is always subject to error and such error can be harmful where the relative positions of the top portions of the femur bones are used in gauging the amount of treatment the bone structure of the person should receive. The present invention obviates the labor and possible errors involved in the use of these mathematical calculations by providing a distortion meter that can, when superimposed upon the X-ray photographic plate, directly indicate the true and exact positions of the objects which cast the shadows shown on the photographic plate. This distortion meter not only accounts for the vertical divergence of the X-rays but it also accounts for the horizontal divergence of the X-rays. As a matter of fact, the distortion meter of the present invention makes it possible to obtain quick and precise determinations of the relative positions of two spaced objects even though one of the objects is spaced a considerable distance farther from the photographic plate than the other is spaced from that plate. It is, therefore, an object of the present invention to provide a distortion meter that compensates for the horizontal and vertical divergence of X-rays.

In the reading of X-ray photographic plates, it is customary to affix the photographic plate to the front of a viewing box and to provide a source of illumination in the box behind the photographic plate. The distortion meter of the present invention can be used with such a box by making the meter of a transparent material, and by securing it to a transparent support that is attached to the viewing box. Moreover, the distortion meter can be pivoted to the transparent support so it can be rotated to any part of the photographic plate to provide accurate reading of all portions of that plate.

The X-rays which emerge from the aperture of the X-ray machine and follow a path that is precisely perpendicular to the plane of the photographic plate will pass through the body of the person being X-rayed in such a way that they will cause the portion of the body immediately in front of the aperture to cast a shadow that has the same position as the aperture, but all of the other X-rays will diverge from that

path and will cast shadows that do not have the same position as the objects through which those rays passed. As a result, one portion of the distortion meter must make no correction for distortion while other portions of the distortion meter must make corrections of varying degree for distortion, and the said one portion of the distortion meter must be superimposed over that part of the photographic plate which was directly opposite the aperture of the X-ray machine. The present invention makes this possible by providing a pivot at that point on the distortion meter which corresponds to the point of impingement of the distortion-free perpendicular path on the photographic plate, and by securing that pivot to a transparent support on an X-ray viewing box so it will overlie the portion of the photographic plate that was opposite the aperture of the X-ray machine. This arrangement not only enables the distortion meter to correct for the distortion of various spaced shadows on the photographic plate, but it also enables the distortion meter to be moved over all portions of the photographic plate to correct for the distortion of all shadows on that plate. It is, therefore, an object of the present invention to provide a viewing box with a transparent support that maintains the pivot of a distortion meter in register with that portion of the photographic plate which was directly opposite the aperture of the X-ray machine.

Other objects and advantages of the present invention should become apparent from an examination of the drawing and accompanying description.

35 In the drawing and accompanying description, a preferred embodiment of the present invention is shown and described but it is to be understood that the drawing and accompanying description are for the purposes of illustration only and do not limit the invention and the invention will be defined by the appended claims.

In the drawing, Fig. 1 is a perspective view of an X-ray viewing box which is equipped with the distortion meter of the present invention, and 45 Fig. 2 is a front elevational view of the distortion meter shown in Fig. 1.

Referring to the drawing in detail, the number 10 denotes an X-ray viewing box which has opaque sides and top and has a translucent plate 50 12 at the front thereof. Bordering the plate 12 is a retaining frame 14 that has spaced, clips 16 attached thereto. The clips 16 extend over and bear against portions of the plate 12. Whenever the edges of a photographic plate are inserted 55 between the clips 16 and the plate 12, that photographic plate will be held in position against the plate 12 by the clips 16. Also mounted on the frame 14 are projecting studs, bolts or screws 18 and the studs 18 support a horizontally disposed transparent support 20. The support 20 has notches 22 at the opposite ends thereof and these notches cooperate with the studs 18 to maintain the support 20 in position relative to the viewing box 10.

65 Positioned in the approximate center of the support 20 is a pivot 24, and this pivot rotatably carries a distortion meter 26. The distortion meter 26 is of transparent material and it has an opening 28 therethrough that can receive and fit over the pivot 24 carried by the support 20. Extending downwardly from the opening 28 is a series of spaced openings 30 that lie on a "True" line which would, if extended, pass through the opening 28. Angularly spaced from the aligned 75 openings 30 of the "True" line are other lines 32,

34, 36, 38 and 40 that are positioned on one half of the meter 26, and angularly spaced from the aligned openings 30 of the "True" line are other lines 42, 44, 46, 48 and 50, that are positioned on the other half of the meter 26. The lines 32, 34, 36, 38, 40, 42, 44, 46, 48 and 50 may be marked on the distortion meter 26 in any suitable manner, but they can easily be inscribed in the material of which the meter 26 is made. Each of the lines 32, 34, 36, 38, 40, 42, 44, 46, 48 and 50 is positioned relative to the opening 28 so extensions of those lines would pass through the opening 28. As a result, the lines 32, 34, 36, 38, 40, 42, 44, 46, 48 and 50 can be said to extend radially outward from the opening 28. Inclined at an angle to the lines 32, 34, 36, 38 and 40 and to the "True" line are a number of straight lines 52 that terminate in the spaced openings 30 of the "True" line. One half of the lines 52 are shown as being dotted, but this is done to make the meter 26 easier to read and, if desired, the dotted lines can all be made solid. Inclined at an angle to the lines 42, 44, 46, 48 and 50 and to the "True" line are a number of lines 54 that also terminate in the spaced openings 30 of the "True" line, and one half of the lines 54 are dotted although, if desired, all of the lines 54 can be made solid.

Adjacent the lower ends of the lines 32, 34, 36, 38 and 40 are figures which correspond to the number of inches between the photographic plate and the object being X-rayed. These figures, which are even numbers, are given in terms of inches and are separated by the common interval of two inches. Accordingly, the reference lines 52 are straight and have the same slope. Adjacent the lower ends of lines 42, 44, 46, 48 and 50 are figures, which are odd numbers and are given in terms of inches. However, it will be noted that while lines 42, 44, 46, 48 and 50 are separated by an interval of two inches, the line 42 is separated from the "True" line by an interval of three inches. Accordingly, while the reference lines 54 have the same slope until they touch line 42, they have a sharper slope between line 42 and the "True" line to compensate for the three inch interval.

Formed on the left hand edge of the distortion meter 26 is a scale 56 that can be a metric or English scale. Only a portion of the scale 56 is shown in the drawing, but the scale 56 will preferably extend along the entire length of the distortion meter 26 so it can be used to measure the distance between points on the photographic plate. The left hand edge of the distortion meter 26 is, and the right hand edge of that meter can be so disposed relative to the opening 28 as to extend axially outward from that opening.

The linear spacing between the aligned openings 30, the angular spacing between lines 32, 34, 36, 38, 40, 42, 44, 46, 48 and 50, and the inclination of the lines 52 and 54 will be determined to a large extent by the perpendicular distance between the photographic plate and the aperture of the X-ray machine, but those spacings can be determined with great precision in each case. With the distortion meter shown, at a reduced scale, in the drawing, the perpendicular distance from the photographic plate to the aperture of the X-ray machine was sixty inches.

According to the principles and teachings of the present invention, a person or object is placed between an X-ray machine and a photographic plate, the distances between the photographic plate and the particular portions of the object or person to be X-rayed are carefully

measured and recorded, and then the X-rays are projected through the body of the person or object and are caused to fall upon the photographic plate. Thereafter, the photographic plate is developed and is held in front of the translucent plate 12 of viewing box 10 by clips 16. Thereupon the support 20 can be set so the notches 22 thereof rest on and are held by the studs 18 and at this time, because of predetermined positioning of the photographic plate relative to the aperture of the X-ray machine, the pivot 24 of the support 20 will overlie that point on the photographic plate which was directly opposite the aperture of the X-ray machine. As a result, telescoping of the opening 28 of the distortion meter 26 over the pivot 24 will correctly position the meter 26 relative to the photographic plate. Once this has been done, the various objects whose true relative heights are to be determined are located on the photographic plate and reference is made to the previously recorded distances between each of those objects and the photographic plate. Thereafter the one particular line, of the group of lines 32, 34, 36, 38, 40, 42, 44, 46, 48 and 50, which most closely corresponds to the distance between the object being measured and the photographic plate is placed so it intersects the shadow cast by that object on the photographic plate. Then, that inclined line, of the groups of lines 52 and 54, which is closest to the intersection of the shadow and the one particular line of the group of lines 32, 34, 36, 38, 40, 42, 44, 46, 48 and 50 is followed to the opening 30 at the end thereof and a pen, pencil or other object is inserted through that opening 30 and is used to make a mark on the photographic plate as the distortion meter 26 is rotated about the pivot 24. This forms an arc on the photographic plate and when the distortion meter 26 is set so its left hand edge intersects the shadow of the object being measured and when a line is drawn along that edge to form an intersection with the arc, that intersection represents the true relative position of the object which cast the shadow on the photographic plate. The intersection will indicate the true vertical position of the object and will also indicate the true horizontal position of the object since the distortion meter 26 compensates for the vertical and horizontal divergence of the X-rays. In other words, the intersection will be the point that was directly opposite the object when the photographic plate was made, and is thus the perpendicular projection of that object. Having established the true position of the one object, the one particular line, of the group 32, 34, 36, 38, 40, 42, 44, 46, 48 and 50, which most closely corresponds to the distance between the photographic plate and the second object is placed so it intersects the shadow cast by the second object. Then, that inclined line, of the groups of lines 52 and 54, which is closest to the intersection of the shadow and the one particular line of the group of lines 32, 34, 36, 38, 40, 42, 44, 46, 48 and 50 is followed to the opening 30 at the end thereof, and a pen, pencil or other object is inserted through that opening 30 and is used to make a mark on the photographic plate as the distortion meter is rotated about the pivot 24. This forms an arc on the photographic plate and when the distortion meter 26 is set so its left hand edge intersects the shadow of the other object and when a line is drawn along that edge to form an intersection with the arc, that intersection represents the true horizontal and verti-

cal position of the second object. A measurement of the position of the two intersections relative to a common base or level will provide a true and accurate indication of the relative positions of the objects which cast the shadows on the photographic plate. In determining the relative positions of the intersections on the photographic plate, a T-square, a try-square or other similar device can be set against the frame 14 and can be used to draw two horizontal lines and two vertical lines through the intersections on the photographic plate. Thereafter, rotation of the meter 26 until its left hand edge is vertical permits the scale 56 on that edge to indicate the distance between the two horizontal lines; rotation of the meter 26 until its left hand edge is horizontal permits the scale 56 to indicate the distance between the two vertical lines. These distances are true indications of the differences between the vertical and horizontal positions of the objects that cast the shadows on the photographic plate.

In some instances, horizontal and vertical lines can be formed in the photographic plate itself and these lines can be used to measure the relative positions of the intersections. In using these lines, the distances between the intersections and any horizontal or vertical line can be measured to provide a measure of the relative positions of the objects which cast the shadows. The lines on the photographic plate can be prepared in a number of ways, but one way utilizes india ink lines in the inner surface of the holder for the photographic plate, and those india ink lines will cast shadows on the photographic plate which will be a permanent part of that plate.

Where the distances between the photographic plate and the objects, whose relative heights are to be determined, are not integral inches, it is necessary to interpolate. Similarly, where the intersection between the shadow on the photographic plate and one of the radially extending lines 32, 34, 36, 38, 40, 42, 44, 46, 48 and 50 does not lie on one of the inclined lines 52 and 54, interpolation is necessary. This can be done visually. In indicating the final interpolated intersection, it would be advisable to make two preliminary arcs through the openings 30 and then to place the interpolated arc at the right distance between them.

Where the objects, whose relative positions are to be measured, are pressed against the photographic plate, and where those objects do not have an appreciable thickness, there will be no distortion, and the true position of such objects can be indicated by placing the "True" line over the shadows cast by those objects and making a mark through the appropriate opening 30 of the "True" line. Where, however, the objects are spaced from the photographic plate, there will be considerable distortion and the appropriate radially extending lines 32, 34, 36, 38, 40, 42, 44, 46, 48 and 50, and the appropriate lines 52 and 54, will have to be used to indicate the true relative positions of those objects.

As indicated in the drawing, the support 20 is preferably located about the middle of the viewing box 10. With this arrangement the meter 26 can be used with the upper and lower portions of the photographic plate.

Whereas a preferred embodiment of the present invention has been shown and described in the drawing and accompanying description, it should be obvious to those skilled in the art that

various changes can be made in the form of the invention without affecting the scope thereof.

What I claim is:

1. A viewing box for X-ray photograph plates that comprises an enclosure with opaque sides and top, a translucent front plate, a source of illumination behind said translucent plate, means to secure a photographic plate adjacent to said translucent plate, a supporting bar of substantially transparent material secured to said enclosure, a pivot carried by said bar, said plate securing means and said supporting bar coacting to cause said pivot to overlie that point on the photographic plate which was directly opposite the aperture of the X-ray machine, and a substantially transparent indicator rotatably secured to said pivot, said indicator having a plurality of spaced openings therethrough, said indicator also having a plurality of lines that extend radially outwardly from said pivot, said indicator also having a plurality of lines that are angularly disposed relative to said radially extending lines and that terminate in said openings, said radially extending lines and said angularly disposed lines being dimensioned and being spaced relative to said openings whereby said indicator can be used in making marks on said photographic plate which will indicate the true positions of the objects that cast shadows on said photographic plate.

2. The method of determining the exact position of a plurality of objects that comprises X-raying said objects, placing the photographic X-ray plate adjacent the translucent front of an X-ray viewing box, superimposing on said photographic plate a distortion meter which has radially extending lines that project outwardly from that point on the X-ray plate which was opposite the aperture of the X-ray machine and that also has angularly disposed lines which intersect said radially extending lines and that terminate in spaced openings, selecting the radially extending lines which correspond to the distances between the photographic plate and objects at the time the X-ray plate was made, selecting the angularly disposed lines which intersect the radially extending lines at the shadows of the objects being measured, following the angularly disposed lines to the openings, making marks through said openings as said meter is rotated, passing lines through each of the shadows and said point of the X-ray plate which was opposite the aperture of the X-ray machine and extending those lines to form intersections with the marks that were made as the meter was rotated, and then comparing the relative position of said intersections.

3. The combination of a support, a distortion meter, and a pivot that extends between said support and said distortion meter and permits rotation of said distortion meter relative to said support, said combination being adapted for use in determining the position of objects that cast shadows on X-ray photographic plates, said distortion meter comprising a transparent body, a series of aligned openings extending radially outwardly from said pivot, angularly spaced lines that extend radially outwardly from said pivot, the angular spacing of said lines being a function of the distances between the photographic plate, and points spaced from that photographic plate, and angularly disposed lines that extend from said aligned openings and intersect said radially extending lines, said radially extending lines including the loci of shadows of points spaced at predetermined distances from the X-ray photo-

graphic plate at the time the X-ray photographic plate was exposed, said support being disposable adjacent a photographic X-ray plate to place said pivot in register with that point in said X-ray photographic plate which was directly opposite the aperture of the X-ray machine.

4. A viewing box for X-ray photographic plates that comprises an enclosure with opaque sides and top, a translucent plate, a source of illumination behind said translucent plate, means to secure a photographic plate adjacent to said translucent plate, a supporting bar of substantially transparent material secured to said enclosure, a pivot carried by said bar, and a substantially transparent indicator rotatably secured to said pivot, said indicator having a plurality of reference points thereon, a portion of said reference points being adapted to be placed in register with the shadows cast on said photographic plate by objects being X-rayed, other of said points being adapted to overlie other portions of the photographic plate and indicate the distances between that portion of the photographic plate which was directly opposite the aperture of the X-ray machine and the perpendicular projections of the objects which cast the shadows.

5. A viewing box for X-ray photographic plates that comprises an enclosure with opaque sides and top, a translucent plate, a source of illumination behind said translucent plate, means to secure a photographic plate adjacent to said translucent plate, a supporting bar of substantially transparent material secured to said enclosure, a pivot carried by said bar, and a substantially transparent indicator rotatably secured to said pivot, said indicator having a plurality of reference points thereon and having a plurality of openings therethrough, said reference points being adapted to be placed in register with the shadows cast on said photographic plate by objects being X-rayed, said openings being adapted to overlie other portions of the photographic plate and indicate the radial distance of the perpendicular projections of the objects that cast the shadows on said photographic plate.

6. The combination of a support, a distortion meter, and a pivot that extends between said support and said distortion meter and permits rotation of said distortion meter relative to said support, said combination being adapted for use in determining the position of objects that cast shadows on X-ray photographic plates, said distortion meter comprising a transparent body, a series of aligned openings extending radially outwardly from said pivot, angularly disposed lines that extend from said aligned openings and define the loci of points at various distances from the divergence-free path of the X-rays, and marks on said lines indicating the distances between said points and the photographic plate when the photographic plate was exposed, said support being disposable adjacent a photographic X-ray plate to place said pivot in register with that point in said X-ray photographic plate which was directly opposite the aperture of the X-ray machine.

7. The combination of a support, a distortion meter, and a pivot that extends between said support and said distortion meter and permits rotation of said distortion meter relative to said support, said combination being adapted for use in determining the position of objects that cast shadows on X-ray photographic plates, said dis-

tortion meter comprising a transparent body, a "True" line on said body, a plurality of lines on said body that are angularly spaced from said "True" line, said plurality of lines defining the loci of all shadows of points spaced at predetermined distances from the photographic X-ray plate, and markings on said body that correlate points on said plurality of lines with corresponding points on said "True" line, said support being disposable adjacent a photographic X-ray plate to place said pivot in register with that point in said X-ray photographic plate which was directly opposite the aperture of the X-ray machine.

15 8. A distortion meter that comprises a transparent body, a "True" line on said body that is disposed radially of a reference point on said body, a plurality of lines that extend radially outwardly from said reference point to define the loci of the shadows of all points that are between the X-ray machine and an X-ray photographic plate and are spaced at certain predetermined distances from said photographic plate, other lines on said body that are angularly disposed to said radially extending lines and that extend to said "True" line to correlate points on said radially extending lines with corresponding points on said "True" line, and an edge of said body being radially disposed of said reference point and being registerable with shadows on said photographic plate, said reference point being an opening around which said body can be rotated, said "True" line having spaced openings therealong to permit a marking implement to be extended to the photographic plate to make markings thereon.

30 9. A distortion meter for use with photographic X-ray plates that comprises a transparent body, a reference opening through said body, a "True" line on said body, a plurality of lines on said body that are angularly spaced from said "True" line, said lines including therein the loci of all shadows of points spaced certain predetermined distances from the photographic X-ray plate, other lines that are inclined to said lines and to said "True" line, a plurality of openings that lie on said "True" line of said meter and are at the termini of said inclined lines, and an edge which extends radially outward from said reference opening, the intersections of said plurality of lines and said inclined lines indicating the positions of shadows cast by objects, the openings on the "True" line indicating the distances between said reference opening and the perpendicular projections of the points which cast said shadows, and the edge cooperating with arcs, formed by the openings as the meter was rotated relative to the photographic plate, to indicate the true position of the points which cast the shadows.

35 10. The method of determining the exact position of a plurality of objects that comprises X-raying said objects, measuring the distance between said objects and the photographic plate which the X-rays struck, developing that photographic plate, drawing lines between the shadows of said objects and that point on the photographic plate which was directly opposite the aperture of the X-ray machine when the objects were X-rayed, superimposing a distortion meter over said photographic plate that will indicate the shortest distances between the divergence-free path for the X-rays and the objects which cast said shadows, and using that meter to indicate the positions on said lines of the perpendicular projection of the objects which cast the

11

shadows, as by locating on that meter points spaced from said divergence-free path of the X-rays distances corresponding to the distances between said divergence-free path and the objects which cast said shadows and superimposing those points over said lines to indicate the "True" positions of the objects which cast the shadows on the photographic plate.

11. The method of determining the exact position of a plurality of objects that comprises X-raying said objects, measuring the distance between said objects and the photographic plate which the X-rays struck, developing that photographic plate, indicating on the photographic plate the loci of all objects that could have cast the shadows on the plate, superimposing on the photographic plate a distortion meter provided with lines that facilitate determination of the shortest distances between that point on the photographic plate which was directly opposite the aperture of the X-ray machine and various points on that plate corresponding to objects at various distances from the X-ray plate, using said distortion meter and the measured distances between the objects being X-rayed and the photographic plate to determine the shortest distances between that point on the photographic plate which was directly opposite the aperture of the X-ray machine and the points on that plate corresponding to the objects which cast said shadows, and using those distances to indicate on the loci the perpendicular projections of the objects that cast the shadows.

12. The method of measuring the true position of objects which cast shadows on a photographic X-ray plate, that comprises establishing the loci of all objects that could have cast said shadows by drawing lines between said shadows and that point on the photographic plate which was directly opposite the aperture of the X-ray machine when the photographic plate was made, superimposing an indicator over said photographic plate, that has lines thereon and openings therethrough which correct for the increased distances between the shadows on the photographic plate and that point on said plate which

12

was directly opposite the aperture of the X-ray machine due to the spacing of these objects from said photographic plate when said photographic plate was exposed, and using that indicator to make marks along said lines that compensate for the divergence of the X-rays passing through said objects, as by inserting a marking implement through said holes when said holes are in register with said lines.

10 13. A distortion meter that comprises a substantially triangular transparent body, a series of aligned openings extending from a point adjacent the apex to a point adjacent the base of said triangle, lines that extend radially from said point adjacent said apex and are angularly spaced apart and that extend to points adjacent the base of said triangle, one of the edges of said triangle being radially disposed of said point adjacent said apex and being registerable with shadows 15 on an X-ray photographic plate and angularly disposed lines that extend from said aligned openings and intersect said radially extending lines, said radially extending lines including the loci of shadows of points spaced at predetermined distances from the X-ray plate at the time the X-ray plate was made.
